CHAIR HAVING SPRING-SUPPORTED
SEAT AND BACKAlbert L. Merkel, Brawley, and Herbert A. Merkel,
San Diego, Calif.

Application March 16, 1948, Serial No. 15,155

5 Claims. (Cl. 155—53)

1

Our invention relates to a chair having spring-supported seat and back, more particularly to a chair having certain novel spring supporting means and the objects of our invention are:

First, to provide a chair of this class which is very comfortable when the economy and simplicity of construction is considered;

Second, to provide a chair of this class having novel track means controlling the vertical movement of the chair seat when the springs suspending the same are extended;

Third, to provide a chair of this class in which the seat and the back thereof move in unison and are suspended by a common means whereby the person sitting in the chair does not slide down the back when the seat portion lowers responsive to the weight of the person sitting in the chair;

Fourth, to provide a chair of this class having novel roller and track means cooperating with suspension springs for supporting a chair seat relatively to the main frame thereof;

Fifth, to provide a chair of this class in which the chair seat and back may be pivoted downwardly at the front edge of the chair seat during which movement the chair seat back pivots in unison forwardly with the downward pivotal movement of the front edge of the chair seat;

Sixth, to provide a chair of this class in which vertical movement of the seat and the seat back is directed on an angle parallel to the inclination of the seat back so that the back and seat of the chair maintain their relative position to the horizontal at all times; and

Seventh, to provide a chair of this class which is very simple and economical in construction, efficient in operation and which will not readily deteriorate or get out of order.

With these and other objects in view as will appear hereinafter our invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a top or plan view of our chair; Fig. 2 is a vertical sectional view thereof taken from the line 2—2 of Fig. 1 and Fig. 3 is an enlarged fragmentary sectional view taken from the line 3—3 of Fig. 2.

Similar characters of reference refer to similar parts and portions throughout the several views of the drawings.

The main frame 1, the tracks 2 and 3, seat

frame 4, rollers 5, suspension springs 6 and 7, seat plate 8 and the seat springs 9 constitute the principal parts and portions of our chair.

The frame 1 is provided with a base portion 1a adapted to rest on the floor and in connection with this portion 1a are uprights 1b having horizontal arm portions 1c connected to the upper ends thereof. Thus, the main frame consists of a rectangular base and four uprights which are connected with the cross arms 1c. Supported by the arms 1c are the suspension springs 6 and 7. These springs 6 and 7 are supported directly beneath the arms 1c by hooks 6a and 7a fixed to said arm portions 1c. The lower ends of the springs 6 and 7 are connected to the brackets 4a and 4b respectively projecting from opposite sides of the seat frame 4. The seat frame 4 is provided with an open rectangular frame portion 4c which is horizontally disposed and connected internally of the horizontal frame portion 4c are springs 9 to the opposite ends of which are connected the seat plate 8. This plate 8 is a thin, substantially flexible plate, adapted to support upholstery thereon. The seat frame 4 is provided with an inclined back supporting portion 4d with which the tracks 2 and 3 are aligned as shown best in Figs. 1 and 2 of the drawings. Connected with the horizontal frame portion 4c and the seat back portion 4d at each side thereof is a trunnion 5a on the outer side of which is mounted the roller 5. Thus, each opposite side of the seat frame 4 is guided by a roller 5 and the tracks 2 and 3 as shown in Fig. 3 of the drawings are channel shaped provided with inwardly extending leg portions 3a. The lower end of each of the tracks 2 and 3 is secured to the horizontal member 1d at each opposite side of the base 1a of the main frame 1. The short bracket 3b is provided in connection with each of the tracks 2 and 3 for supporting the upper end of the same in connection with one of the vertical uprights 1b of the main frame 1, all as shown best in Fig. 2 of the drawings. Interconnecting the horizontal seat frame portion 4c and the back 4d are angular braces 4e which provide rigidity of the overall seat frame structure, all as shown best in Fig. 2 of the drawing. It will be here noted that the main frame 1 and the seat frame 4 may be upholstered and the springs 6 and 7 inwardly of the inner edges of the arms 1c are substantially hidden from view behind the upholstery providing a very neat upholstery arrangement of our chair. When the chair is upholstered the seat is raised four or five inches above the seat frame by a foam rubber cushion or cushion having

inner-springs arranged in the usual manner. A cardboard or other light partitioning means is positioned over the inside edges of the arm frames, extending below the seat cushion and terminating slightly above the brackets 4a and 4b. The arm upholstery covers the light weight partitioning means to present a well tailored appearance to the finished upholstered chairs.

The operation of our chair is substantially as follows:

When a person sits in our chair over the plate 8, the springs 6 and 7 are extended and the rollers 5 roll downwardly in the tracks 2 and 3 until the weight of the person is balanced. If the weight of the person is forward on the horizontal seat frame portion 4c near the front edge 4f thereof, the spring 7 will be extended a greater distance than the spring 6 and the back portion 4d of the frame 4 will tilt forwardly in conforming relationship to the downwardly tilted disposition of the forward edge 4f of the horizontal frame portion 4c. It will be noted that both the frame portions 4c and 4d pivot about the axis of the roller 5 in the track 3 and that when the seat frame 4 moves downwardly it always moves parallel to the tracks 2 and 3 so that the normal angle of the back 4d with respect to the horizontal is maintained. The thin plate 8 being flexible and supported by surrounding spring 9 provides very efficient and comfortable support for the cushion of the upholstery placed thereover. Brackets 4a and 4b, extending outwardly of the horizontal frame portion 4c of the seat 4 project beneath the arms 1c of the main frame 1 in order to hide the springs 6 and 7 inwardly of the chair arms 1c in which they operate freely.

Though we have shown and described a particular construction, combination and arrangement of parts and portions, we do not wish to be limited to this particular construction, combination and arrangement but desire to include in the scope of our invention the construction, combination and arrangement substantially as set forth in the appended claims.

Having thus described our invention what we claim as new and desire to secure by Letters Patent is:

1. In a chair, the combination of a main frame having arm portions at opposite sides of said frame, a seat frame having a back fixed thereto intermediate the arm portions of said main frame and springs connected to said arm portions and said seat frame for supporting said seat frame in said main frame, track means aligned with said back and extending downwardly relatively to the arms of said main frame and rollers on opposite sides of said seat frame in said track for guiding the vertical movement of said seat frame in said main frame when said springs are extended.

2. In a chair, the combination of a main frame having arm portions at opposite sides of said frame, a seat frame having a back fixed thereto intermediate the arm portions of said main frame and springs in connection with said arm portions and said seat frame for supporting said seat frame in said main frame, track means aligned with said back and extending downwardly relatively to the arms of said main frame and rollers on opposite sides of said seat frame in said track for controlling the vertical movement of said seat frame in said main frame when said springs are extended, said seat frame having only one roller on each opposite side

thereof providing a horizontal axis on which said seat frame is pivotal when uneven extension of said spring occurs.

3. In a chair, the combination of a main frame having arm portions at opposite sides of said frame, a seat frame having a back fixed thereto intermediate the arm portions of said main frame and springs in connection with said arm portions and said seat frame for supporting said seat frame in said main frame, track means aligned with said back and extending downwardly relatively to the arms of said main frame and rollers on opposite sides of said seat frame in said track for controlling the vertical movement of said seat frame in said main frame when said springs are extended, said seat frame having only one roller on each opposite side thereof providing a horizontal axis on which said seat frame is pivotal when uneven extension of said spring occurs, said springs disposed beneath the arms of said main frame and inwardly of the inner edges thereof, said seat frame having outwardly extending brackets to which said springs are connected.

4. In a chair, the combination of a main frame having arm portions at opposite sides of said frame, a seat frame having a back fixed thereto intermediate the arm portions of said main frame and springs connected to said arm portions and said seat frame for supporting said seat frame in said main frame, track means aligned with said back and extending downwardly relatively to the arms of said main frame and rollers on opposite sides of said seat frame in said track for guiding the vertical movement of said seat frame in said main frame when said springs are extended, said tracks being parallel to the seat back for determining the path on said seat back when said seat frame is vertically moved, and determining in part the angle to the horizontal of the said path of the seat and back.

5. In a chair, the combination of a main frame having arm portions at opposite sides of said frame, a seat frame having a back fixed thereto intermediate the arm portions of said main frame and springs connected to said arm portions and said seat frame for supporting said seat frame in said main frame, track means aligned with said back and extending downwardly relatively to the arms of said main frame and rollers on opposite sides of said seat frame in said track for guiding the vertical movement of said seat frame in said main frame when said springs are extended, said tracks being channel shaped in cross section, said seat frame having trunnions extending therefrom on which said rollers are mounted.
